CLAIM

The ornamental design for a choke tube for shotgun, as shown and described.

DESCRIPTION

FIG. 1 is a front perspective view of the choke tube for shotgun;

FIG. 2 is a left-side view of the choke tube for shotgun;

FIG. 3 is a right-side view of the choke tube for shotgun;

FIG. 4 is a top view of the choke tube for shotgun;

FIG. 5 is a bottom view of the choke tube for shotgun;

FIG. 6 is a front view of the choke tube for shotgun;

FIG. 7 is a rear view of the choke tube for shotgun; and,

FIG. 8 is a right-side view of the choke tube for shotgun, in a use configuration mounted on environment of a shotgun.

The broken line in FIG. 7 depicts a portion of the choke tube for shotgun that forms no part of the claimed design.

FIG. 8 includes broken lines depicting the environment of a shotgun that forms no part of the claimed design.

1 Claim, 8 Drawing Sheets
